UNITED STATES PATENT OFFICE

EDWARD J. CANAVAN, OF WOODCLIFF, NEW JERSEY, ASSIGNOR TO THE BARRETT COMPANY, A CORPORATION OF NEW JERSEY

SULPHURIZED-PHENOLS AND PROCESS OF MAKING

No Drawing.

Application filed January 29, 1926. Serial No. 84,750.

This invention relates to reagents for use in the separation of valuable minerals from their ores by flotation and to the process of preparing and using this reagent for flotation purposes. It relates more particularly to reagents of this character that are prepared from certain tar distillates or extractions therefrom.

Those crude tars which are commercially known as coal tar, blast furnace tar, lignite tar, wood tar and others, contain acids which are commercially known as phenol, cresols and xylenols. These acids occur in those fractions of the tar distillate which are known as carbolic oil and creosote oil (both of which are sometimes designated as "carbolic oil" or "middle oil"). These acids are quite often separated from any tar distillate in which they occur, by causing them to unite with caustic soda. Those acids to which we refer would, in most cases, be those which are extractable from the above tars or distillates by caustic soda and are referred to in the specification and claims as "tar acids". By the present invention a very satisfactory flotation reagent is produced by a process which is efficient and convenient to employ.

In carrying out this invention an autoclave of the well known type, or any device in which may be placed materials to be heated and agitated under pressure, is used; sulphur, as such, is caused to unite therein, at an elevated temperature and pressure, with tar acids such as phenol, cresols and xylenols. The resulting compound may be used in its concentrated form as a reagent for flotation purposes or may be mixed with coal tar, coal tar oil or other oil and thus used as a flotation agent.

As an illustration of practicing my invention, but by which I have no intention of being limited, it may be stated that I have found it very efficient to carry out my process as follows: Between five and six parts by weight of the tar acid to be treated and one to two parts by weight of sulphur, i. e. in amounts equivalent to about 16-40% by weight of the tar acid, are placed in an autoclave or other pressure vessel which is then closed. The

temperature of the mixture is elevated by the application of heat to the mixture until the reaction takes place and is completed, H_2S being evolved. The autoclave, or whatever pressure vessel may be used, is provided with a safety valve or pressure release so adjusted as to maintain the pressure, created by the formation of H_2S , in the vessel at approximately 50 pounds pressure per square inch. One of the objects of maintaining the pressure at approximately this point is to be able to increase the temperature of the mixture to about $230^\circ C.$, at approximately which temperature the most efficient results have been found to be obtained. In fact the materials will only react slowly at the atmospheric boiling point of the acids used. Hence, to make this method commercially possible, the elevated boiling point is necessary.

The above proportions of the materials used apply to either the treatment of a single tar acid (phenol, cresol or xylene) or to a mixture of these tar acids. Of course, it is to be understood, and I have found, that these proportions may be varied over a considerable range. For instance, if the tar acid is crude and impure, less sulphur may be required to complete the reaction, or if the sulphur used is of a poor quality, more sulphur may be required. In other words, the sulphur added is dependent upon the tar acid content of the crude acid and is added or admixed with the crude acid preferably in sufficient amount to substantially completely react with the tar acids contained therein.

In some cases it may be desirable to agitate the mass in order to more thoroughly promote the reaction.

These variations all depend upon the material being treated and a number of minor variations will doubtless occur to anyone skilled in the art. It is intended, therefore, that all variations of this nature shall be included in the claims.

It is thought unnecessary to further describe the use of this product, since those skilled in the art are quite familiar with flotation processes. It may be said, however, that very small quantities of this reagent are

sufficient for the proper flotation of a large quantity of ore.

Furthermore, this reagent can be produced quite uniform in quality and is stable under shipping and storage conditions.

I claim:

1. The process which comprises treating tar acid with sulphur at a temperature above the atmospheric boiling point of the mixture.

10 2. The process which comprises treating tar acid with sulphur at a pressure greater than atmospheric and at a temperature above the atmospheric boiling point of the mixture.

15 3. The process which comprises agitating tar acid with sulphur at a pressure greater than atmospheric and at a temperature above the atmospheric boiling point of the mixture.

20 4. The process which comprises treating a mixture of phenol, cresol and xylol with sulphur at a pressure greater than atmospheric and at a temperature above the atmospheric boiling point of the mixture.

25 5. The process which comprises treating tar acid with sulphur at a pressure of approximately 50 pounds per square inch and at a temperature of approximately 230° C.

30 6. The process which comprises treating phenol with sulphur at a pressure greater than atmospheric and at a temperature above the atmospheric boiling point of the mixture.

35 7. The process which comprises treating phenol with sulphur at a pressure of approximately 50 pounds per square inch and at a temperature of approximately 230° C.

40 8. A composition of matter comprising tar acid which has been treated with sulphur at a pressure greater than atmospheric and at a temperature above the atmospheric boiling point of the mixture.

45 9. A process of treating tar acids which comprises admixing a sufficient quantity of sulphur with said acids to substantially completely react therewith, and heating said admixture of acids and sulphur at a temperature above the atmospheric boiling point of said acids until the reaction is substantially complete.

50 10. A process of treating tar acids which comprises admixing with said acids about 16-40% of their weight of sulphur, and heating said admixture of acids and sulphur at a temperature above the atmospheric boiling point of said acids until the reaction is substantially complete.

55 11. A process of treating tar acids which comprises admixing with said acids about 16-40% of their weight of sulphur, and heating said admixture of acids and sulphur under pressure at a temperature above the atmospheric boiling point of said acids until the reaction is substantially complete.

60 12. A process of treating tar acids which comprises admixing with said acids about 16-40% of their weight of sulphur, and heating said admixture of acids and sulphur at a

temperature of approximately 230° C. until the reaction is substantially complete.

65 13. A process of treating tar acids which comprises admixing with said acids about 16-40% of their weight of sulphur, and heating said admixture of acids and sulphur under pressure at a temperature of approximately 230° C. until the reaction is substantially complete.

70 14. A composition of matter comprising the product resulting from the reaction of tar acid with sulphur under pressure.

75 15. A composition of matter comprising the product resulting from the reaction of tar acid with sulphur at temperatures above the atmospheric boiling point of the mixture.

80 16. A composition of matter comprising the product of the reaction of tar acid with from 16% to 40% of its weight of sulphur.

85 17. A composition of matter comprising the product resulting from the reaction of tar acid with from 16% to 40% of its weight of sulphur at a temperature of about 230° C. and under a pressure of about 50 pounds per square inch.

In testimony whereof I affix my signature.

EDWARD J. CANAVAN.
